UNITED STATES PATENT OFFICE

ERNEST A. HALL, OF TOLEDO, OHIO, ASSIGNOR TO THE HALL MANUFACTURING COMPANY, OF TOLEDO, OHIO, A CORPORATION OF OHIO

CYLINDER HONE

Original application filed March 25, 1926, Serial No. 97,240. Divided and this application filed July 28, 1928. Serial No. 295,890.

This invention relates to tools for grinding or honing internal walls of engine cylinders, and objects are to provide a simple and efficient tool of the above character having the new and improved features of construction hereinafter described.

A particular object of this invention is to produce novel means for yieldingly and non-yieldingly limiting the outward movements or adjustments of the stone or abrading-
holder elements.

This constitutes a division of United States Patent No. 1,696,477, dated December 25th, 1928, to Ernest A. Hall and Gerald J. Lindroth.

For purposes of illustration, and not of limitation, the invention is shown on the accompanying drawings, in which:

Figure 1 is a longitudinal sectional elevation of a cylinder grinding tool or hone;

Figure 2 is a transverse sectional view on the line 2—2 of Figure 1;

Figure 3 is a transverse sectional view on the line 3—3 of Fig. 1; and

Figure 4 is a fragmentary view in longitudinal section of an alternate form.

The illustrated embodiment of the invention comprises a tool body 1 having a central bore 2 extending longitudinally therethrough, and having in equidistantly spaced relation around its outer side, longitudinal apertured bearing bosses 3 extending lengthwise of the body with their apertures parallel to the body axis. The body 1 is substantially rectangular in cross section, and has at each corner an extension forming a bearing boss 3 in the form shown. Each boss 3 has a pivot pin 4 projecting through its aperture, and a carrier 5 for a stone or abrading member is carried by each pin for transverse swinging movements relative to the body. In this instance, the pins 4 project beyond both ends of the respective bearing bosses, and the carriers have arms which engage the pins at the ends of the bosses, these arms being disposed at the ends of the carriers. The abrading members 6 are set in channeled portions of the carriers, and are secured therein in any suitable manner, as by set screws (not shown).

A shaft 10 is feathered in the bore 2 of the body 1 to permit it to have axial movements relatively thereto, and to cause the body to rotate therewith. The shaft 10 at each end of the body 1, and within the limits of the respective ends of the carriers 5, is provided with a cone 11, the outer end of which is removably carried by the shaft to permit its removal preparatory to removing the shaft from or inserting it into the body 1. The removable cone, in the form shown, is screwed on the lower extended or outer end portion of the shaft, and is securely held in shouldered engagement with the shaft by a nut 12. The two cones 11 face or have their tapers extending in the same direction, and are fixed to the shaft against any relative longitudinal movements. In this instance, the smaller ends of the cones face toward the outer end of the shaft 10.

Each carrier 5, at the inner side of each end thereof, is provided with a tapered boss or projection 13, which opposes and is complementary to the tapered surface of the adjacent cone 11, so that the inward swinging movements of the carriers relative to the body are stopped by the cones, and axial movements of the shaft 10 and its cones will permit either a further inward movement of the carriers, or will cause positive uniform outward movements thereof, depending on the direction of movement of the cones.

The shaft 10 extends outwardly beyond the body 1, and is provided at its outer end in suitable spaced relation with means for attaching it to a motor shaft, drill press spindle, or other suitable driving means. The attaching means, in the form shown, consists of a socket member 15.

Means are provided for effecting a continued outward yielding movement of the carriers 5 during an operation of the tool, where such action is desired, and for this purpose a sleeve support 16 extends outwardly from the body 1, and is internally screw-threaded. Disposed within the sleeve support 16 and surrounding the drive shaft 10, is a coiled compression spring 17, which bears at one end against the end of the adjacent cone 11. A nut or sleeve 18 is externally screw-threaded

ed, and is screwed into the sleeve support 16, bearing against the opposite end of the spring 17.

It is to be understood that when the abrading portion of the tool is inserted into a cylinder to be ground, and the nut 18 adjusted to compress the spring 17 and cause an outward grinding pressure of the abrading members against the cylinder wall, the rotary grinding action of the tool will continue until a predetermined part of the surface of the wall has been removed, the spring functioning until the abrading members have been extended to such a degree that the pressure of the spring has been compensated for. When it is desired to remove but a small part of the cylinder wall the spring pressure is relieved accordingly, it being manifest that the compression of the spring determines the amount of the surface wall to be removed.

In the alternate form shown on Fig. 4, the sleeve support 16^a extends outwardly from the body 1, but instead of being internally screw-threaded substantially its entire length, as in the form shown in Fig. 1, the upper portion only is screw-threaded. In threaded engagement with the screw threaded portion of the support 16^a is an elongate gland nut 19, the inner end of which is adapted to bear against the outer end of the adjacent cone 11. When this nut is turned down with its lower end in engagement with the cone 11, it is evident that inward axial movement of the shaft 10 is prevented so that the tool will not grind the cylinder wall to a greater diameter than that for which the stones or abrading elements 6 are originally set, because there is no provision for permitting the abrading elements to receive a yielding outward pressure to continue the grinding action beyond the point for which the cones are set.

In this form, provision is also made for securing a continued outward yielding movement of the carriers by means of a coil spring 17^a, which is disposed within the gland nut 19, and bears at one end against the outer end of the adjacent cone. A nut 18^a is in threaded engagement with the screw threaded bore of the sleeve nut 19. As hereinbefore described, the nut 18^a may be adjusted to vary the tension on the spring 17^a to exert a yielding outward pressure on the abrading element 6 when the tool is moved longitudinally in one direction.

In both forms above described, it is apparent that movement of the tool into the cylinder to be ground causes the outward extension of the abrading element 6 due to the direction of taper of the cones 11, but movement of the tool in the opposite direction relieves the expanding or extending pressure on the abrading elements. It is apparent that when the sleeve nut 19 is turned down to

engage the cone 11, no expanding of the abrading elements takes place.

In practice, it is desirable, when first truing a cylinder, to apply the spring expanding action to the abrading elements 6 so that the grinding will continue until a predetermined initial portion of the cylinder wall has been removed. When the cylinder has been ground in this manner to substantially the diameter desired, the spring tension is relieved and the stop sleeve or sleeve nut 19 turned down to give a positive set adjustment to the abrading members, so as to surface and accurately grind the cylinder in the manner desired.

While I have described my improved tool in more or less detail to comply with the requirements of the statute, it is nevertheless desired that this detailed description be considered merely as illustrative and not as limiting, and it is to be understood that changes and modifications may be made by those skilled in this art without departing from the invention as defined in the pending claims.

What I claim as new and desire to secure by Letters Patent is:

1. In a tool of the class described, a rotatable body, a shaft for driving said body and capable of limited axial movements relatively thereto, a pair of corresponding cones carried in fixed spaced relation by the shaft and facing in the same direction, elongate abrading stone carriers carried by the body in spaced relation around the same and with their longitudinal axes disposed lengthwise of the shaft, each of said cones having coaction with said carriers, whereby any movement of the shaft in one direction will impart like outward movements to both ends of the carriers, tension means bearing directly against one of said cones, a housing fixed to said body and enclosing said tension means, and an element adjustable in said housing providing an abutment for the opposite end of said tension means for regulating the same.

2. In a tool of the class described, a rotatable body, a shaft for driving said body and capable of limiting axial movements relatively thereto, a pair of corresponding cones carried in fixed spaced relation by the shaft and facing in the same direction, elongate abrading stone carriers carried by the body in spaced relation around the same and with their longitudinal axes disposed lengthwise of the shaft, each of said cones having coaction with said carriers whereby any movement of the shaft in one direction will impart like outward movements to both ends of the carriers, a sleeve on said body, tension means within said sleeve acting on said shaft and body for yieldingly opposing a movement of the shaft in one direction relative to the body, an adjustable element in said sleeve operable to limit positively to any predetermined

mined extent the movement of the shaft in one direction relative to the body, and a member within said element for adjusting the pressure exerted by said tension means.

- 5 3. In a tool of the class described, a body, a plurality of abrading stone-holding members carried by the body for swinging movements transversely thereof and each having longitudinally spaced surfaces, a shaft in driving connection with the body and adapted to have limited axial movements relatively thereto, said shaft having tapered portions which are fixedly spaced axially thereof and facing in the same direction for coaction with 10 said longitudinally spaced surfaces of the stone-holding members, a sleeve on said body, a member in said sleeve in threaded engagement therewith, spring means within said sleeve coacting with said member and body 15 to effect a predetermined yielding adjustment of said shaft and body, and means coacting with said shaft and body for effecting a predetermined positive set adjustment of the shaft and body.
- 20 4. In a tool of the class described, a body, an abrading stone holding member carried by the body for transverse swinging movements relative thereto, a shaft extending axially through said body in driving engagement therewith, a fixed portion on said shaft receiving the inward thrust of said abrading member and adapted to cause positive outward adjustment of the abrading member upon movement of the shaft in one direction, 25 a housing on said body, a coiled spring within said housing and bearing against said body, a sleeve threaded into said housing to form a positive stop for limiting the movement of said shaft in one direction, and an element in 30 threaded engagement with said sleeve and engageable with said spring for adjusting the tension thereof.

- 40 5. In a tool of the class described, a body, a plurality of abrading elements, means connecting said abrading elements to said body for outward swinging movements transversely thereof, a shaft extending axially through said body, means coacting with said shaft and body for effecting outward adjustment of said abrading elements upon axial movement of said shaft in one direction, a sleeve support extending from said body, adjustable tension means within said support for yieldingly opposing movement of said shaft in one direction relative to the body, and adjustable means within said support to limit positively to any predetermined extent movement of the shaft in one direction relatively to the body.

- 55 6. In a tool of the class described, a body, a plurality of abrading elements, means connecting said abrading elements to said body for outward swinging movements transversely thereof, a shaft extending axially through said body, means coacting with said

shaft and body for effecting outward adjustment of said abrading elements upon axial movement of said shaft in one direction, a sleeve support on said body, and adjustable means within said support to limit positively to any predetermined extent movement of the shaft in one direction relatively to the body.

7. In a tool of the class described, a rotatable body, an elongate abrading member carried by the body for outward movements relative to its axis, drive means movable lengthwise of the body and abrading member and having a fixed portion receiving the inward thrust of the abrading member and, when moved in one direction lengthwise of the abrading member, causing an outward positive adjustment thereof, a housing secured to said body and extending outwardly therefrom, a coiled spring in said housing bearing directly against said fixed portion, and an adjustable abutment member carried by said housing for the opposite end of said spring.

In testimony whereof I have hereunto signed my name to this specification.

ERNEST A. HALL.
